CLAIM

The ornamental design for a stacked square tube receiver hitch, as shown and described.

DESCRIPTION

FIG. 1 is a perspective view of the stacked square tube receiver hitch;

FIG. 2 is a top view of the stacked square tube receiver hitch of FIG. 1;

FIG. 3 is a bottom view of the stacked square tube receiver hitch of FIG. 1;

FIG. 4 is a back view of the stacked square tube receiver hitch of FIG. 1;

FIG. 5 is a front view of the stacked square tube receiver hitch of FIG. 1;

FIG. 6 is a left side view of the stacked square tube receiver hitch of FIG. 1; and,

FIG. 7 is a right side view of the stacked square tube receiver hitch of FIG. 1.

“The portions of the stacked square tube receiver hitch shown in hidden lines are provided to show context and form no part of the claimed invention.”
